UNITED STATES PATENT OFFICE

ROBERT A. STEVENSON, OF LANCASTER, OHIO

BATTERY HAND LAMP

Application filed November 11, 1930. Serial No. 494,847.

My invention relates to battery hand lamps.

In the usual battery hand lamps having two dry cells positioned side by side the positive electrode of one dry cell is connected with the negative electrode of the other dry cell either by soldering a connection between the electrodes or by providing some other electrical connection between the cells. There is danger of such connections becoming broken or separated. Also when there is some connection between the cells there is more danger of a short circuit or a leakage of the electricity than if the dry cells are electrically isolated as in my invention.

One object of this invention is to provide a battery hand lamp in which the dry cells are normally electrically isolated, it being unnecessary when constructing it to make any permanent electrical connection between the dry cells.

Another object is to provide a battery hand lamp in which wrapping and soldering will be reduced to a minimum and in which no sealing wax will be necessary except the usual amount in the top of each dry cell.

Another object is to provide a novel method of mounting a lamp bulb on a battery.

Further objects and advantages will appear in the description.

Certain features of this invention are shown in my co-pending application No. 458,394, filed May 31, 1930.

Referring to the drawing in which like numerals refer to like parts, Figure 1 is a cross sectional view of my invention with parts in elevation. Figure 2 is an edge view. Figure 3 is a top view with the lamp bulb removed.

In Figure 1 two dry cells 1 and 2 are arranged side by side with cell 1 in reversed position with relation to cell 2. An insulating case or covering 3 for the cells may be made of cardboard or other insulating material. This case extends above the top of the cells to provide a combined reflector and guard for the lamp. The inside of the portion extending above the cells is preferably painted white or provided with some reflecting material.

Clamped or soldered to the zinc can or

negative electrode of the cell 1 near the top of the device is a metal lamp holder and reflector 4. It consists of a strip of metal provided with a threaded hole or socket 5 for a lamp bulb 6 so that when the lamp bulb is screwed into the socket the inner terminal 7 of the lamp bulb will be held in contact with the carbon electrode cap 8 of cell 2. Part of the lamp holder 4 is bent upward to form a reflector for the lamp bulb.

The cell 2 is provided with an insulating cap 9 made of paper or the like placed over the top of the cell and extending down the sides a short distance. A hole in the center of this cap permits the carbon electrode cap 8 to make contact with the inner terminal 7 of the lamp bulb. A second insulating cap 10 is provided on the bottom of the cell 2 to insulate the bottom and a portion of the sides. These insulating caps insulate the cells 1 and 2 from each other but if desired a strip of paper may also be used between them.

To the carbon electrode cap 11 of cell 1 is clamped or soldered a spring metal contact element 12 which extends along the bottom of the battery hand lamp and provides a bottom therefor. This contact element 12 is bent to extend up the side of cell 2 and between the covering 3 and the insulating caps 9 and 10. At the upper end of the contact element 12 is a threaded hole into which a thumb screw 13 is adapted to be screwed. The thumb screw 13 passes on through the insulating cap 9 and makes contact with the zinc electrode of the cell 2 and thus closes a circuit through the lamp. Unscrewing the thumb screw 13 breaks the contact.

Intermittent operation of the lamp may be secured by pressing on the covering 3 and against the contact element 12 on the edge of the battery hand lamp and between the two insulating caps 9 and 10 to bring the contact element 12 into contact with the zinc electrode of cell 2. The springiness of the contact element 12 will cause it to spring back and away from the cell 2 when the pressure is released thus breaking the contact. Since pressure must be applied at a particular place on the contact element to

operate it I prefer to place an indicating mark 14 on the outside of the covering 3 as shown in Figure 2.

It is seen that accidental pressure on the edge of the hand lamp where these two switches are located will not operate them for pressure on the thumb screw will not force it into contact with the cell 2 because of the insulating cap 9 nor will pressure on the contact element 12 at any other place than that indicated by the mark 14 cause it to touch the cell 2 and close the circuit. The thumb screw also protects the contact element from accidental pressure since it extends out from the edge of the hand lamp. The operator may use either the intermittent switch or the continuous switch as preferred since they are separate in operation and should anything affect the operation of one the other may be used.

It is seen that by my arrangement when there is no lamp bulb in the holder 4 that the two cells are electrically isolated, there being no connection between them and therefore the voltage between the cells is reduced. The accidental contact of the lamp holder 4 with the carbon electrode of cell 2 will not short circuit the cells unless one of the switches is operated at the same time. Also without the lamp bulb in place either switch may be operated without short circuiting the cells.

If desired the operator may remove and discard the thumb screw if he does not care to have it on the side of the hand lamp and its removal will not disfigure the appearance of the hand lamp or affect the operation of the intermittent switch.

In some cases I may prefer to place the thumb screw on the bottom of the hand lamp instead of on the side and have it touch the bottom of cell 2, and if desired I may use a metal casing around the outside of this battery hand lamp to add to its durability and appearance. Furthermore it is understood that various other changes may be made in the position of the switches and in the size, shape and arrangement of parts without departing from the spirit of my invention or the scope of the subjoined claims.

Having thus described my invention, I claim:—

1. A battery hand lamp comprising two electrically isolated dry cells having positive and negative electrodes, lamp holding means attached to one electrode of one dry cell for holding a lamp bulb in contact with one electrode of the other dry cell, circuit closing means for closing a circuit between the dry cells and the lamp, said circuit closing means including a contact element attached to the other electrode of the first mentioned dry cell and adapted to be brought into intermittent contact with the other electrode of the second

mentioned dry cell when certain portion of said contact element is pressed.

2. A battery hand lamp including two electrically isolated dry cells having positive and negative electrodes, lamp holding means mounted upon the negative electrode of one dry cell for holding a lamp bulb in contact with the positive electrode of the other dry cell, circuit closing means comprising a single strip of metal attached to the positive electrode of the first mentioned dry cell whereby said strip may be brought into intermittent contact with the negative electrode of the second mentioned dry cell when manual pressure is exerted upon a certain portion of the said strip of metal.

3. A battery hand lamp including electrically isolated dry cells having positive and negative electrodes, lamp holding means attached to one electrode of one dry cell for holding a lamp bulb in contact with one electrode of another dry cell, circuit closing means for closing a circuit between the dry cells and the lamp, said circuit closing means including a contact element attached to one electrode of one dry cell and adapted to be brought into electrical contact with another electrode of another dry cell.

4. A battery hand lamp including two electrically isolated dry cells having positive and negative electrodes, lamp holding means attached to one electrode of one dry cell for holding a lamp bulb in contact with one electrode of another dry cell, circuit closing means for closing a circuit between the dry cells and the lamp, said circuit closing means including a contact element attached to one electrode of one dry cell and adapted to be brought into both intermittent and continuous electrical contact with another electrode of another dry cell.

5. A battery hand lamp including two electrically isolated dry cells each having a positive and a negative electrode, lamp holding means attached to one electrode of one dry cell for holding a lamp bulb in contact with one electrode of another dry cell, a reflector for the lamp bulb, circuit closing means for closing a circuit between the dry cells and the lamp, said means including a contact element attached to one electrode of one dry cell and adapted to be brought into electrical contact with another electrode of another dry cell.

6. A battery hand lamp including two electrically isolated dry cells each having a positive and a negative electrode, lamp holding means attached to one electrode of one dry cell for holding a lamp bulb in contact with one electrode of another dry cell, circuit closing means for closing a circuit between the dry cells and the lamp, said means including a contact element attached to one electrode of one dry cell and adapted to be brought into intermittent contact with another electrode of another dry cell, and a thumb screw at

- tached to the contact element and adapted to be screwed into direct contact with one electrode of one dry cell to provide a continuous circuit through the lamp.
- 5   7. A battery hand lamp comprising electrically isolated dry cells having positive and negative electrodes, lamp holding means attached to one electrode of one dry cell for holding a lamp bulb in contact with one electrode of another dry cell, circuit closing means including a contact element provided adjacent the side of the battery and beneath the battery covering, two spaced insulating portions located between the said contact element and the battery whereby pressure against the contact element between the two insulating portions will cause the contact element to make direct contact with the side of the battery and close a circuit through a lamp.
- 10   15   20   In testimony whereof I affix my signature.
ROBERT A. STEVENSON.
